UNITED STATES PATENT OFFICE.

MICHAEL GARLAND, OF BAY CITY, MICHIGAN.

CONVEYER-CHAIN.

No. 850,149.

Specification of Letters Patent.

Patented April 16, 1907.

Application filed September 15, 1905. Serial No. 278,565.

To all whom it may concern:

Be it known that I, MICHAEL GARLAND, a citizen of the United States, residing at Bay City, in the county of Bay and State of Michigan, have invented certain new and useful Improvements in Conveyer-Chains; and I do hereby declare the following to be a full, clear, and exact description of the invention, such as will enable others skilled in the art to 10 which it appertains to make and use the same.

This invention is an improvement in conveyer-chains, and relates more particularly to improvements in conveyer-chains of the 15 class illustrated in Patent No. 743,070, issued to me November 3, 1903, which class of chains is especially adapted for conveying sawdust and other material of like nature.

The present improvement pertains particularly to devices used in connection with a conveyer-chain link of any suitable or usual form, whereby the link is made capable of 20 acting effectually as a conveyer or scraper.

It has heretofore been common to attach 25 laterally-extending wings to conveyer-chain links for this purpose; but these wings have been made with vertical front or working faces, and the wings have been extended at right angles to the line of travel of the chain.

30 In practice it is found that the tendency of such a chain is to ride on top of the material to be conveyed, and it is not uncommon to see the material a foot or more deep under the chain.

35 The object of my present improvement is to obviate this difficulty and to provide a scraper attachment that will not only keep the conveyer-trough clean but will, by reason of its form, tend to hold the conveyer-chain down 40 to the bottom of the trough and to draw the material from the sides of the trough toward the center line of the chain instead of allowing the material to escape around the extreme ends of the conveyer-chain wings.

45 With these objects in view my invention consists in the devices illustrated in the accompanying drawings and the equivalents thereof.

Figure 1 is a top plan view showing two 50 links of a chain having my improvement. Fig. 2 is a side elevation of the same.

As is clearly shown in the drawings, the device consists in chain-links 1, which may be of any suitable or convenient form—as, 55 for instance, the ordinary link belt, which is illustrated in the drawings. To such a link

I secure (preferably by casting integral with the links) a pair of laterally-extending wings 2 2, the front or working faces of which are rearwardly beveled or inclined from the bottom edge up, so that the working face has a backward tilt as the chain moves forward in the direction of the arrow. The wings 2 2 are preferably arranged not at right angles to the line of travel of the chain but having their lateral or outer free ends slightly in advance of the inner ends by which they are attached to the link, the effect of this arrangement being to draw the material toward the center line of the chain as the chain advances 70 and prevent the material from escaping around the outer extremity 3 of the wing. I also prefer to form the front 4 of the link-socket with a flat rearwardly and upwardly beveled or inclined face, so that the front of 75 the socket acts as a scoop. To increase the conveying capacity of this part of the link, I prefer to extend the front 4 up above the top surface of the side member 1^a of the link 1, making the top edge of the face 4 about level 80 with the top edge of the wing 2, thus forming a scoop-front on the link. It is found in practice that this rearwardly and upwardly beveled or inclined scoop-front in combination with the rearwardly and upwardly beveled or inclined wings 2, which are also set obliquely to the line of travel of the chain, not only increase the carrying capacity of the chain while permitting it to run more easily, but also prevent the chain climbing or riding 85 upon the material.

I may also provide the braces 5 5 extending obliquely from the links 1 1 and engaging the rear faces of the laterally-projecting wings 2 2, preferably near the outer ends of 95 the wings to strengthen the latter.

What I claim as my invention, and desire to secure by Letters Patent, is as follows:

1. The combination with a conveyer-chain link of laterally-extending wings carried by 100 said link, said laterally-extending wings having their front faces inclined rearwardly and upwardly for the purposes set forth.

2. The combination with a conveyer-chain link of laterally-extending wings carried by 105 said link, said laterally-extending wings having their front faces inclined rearwardly and upwardly; together with a socket having its front face beveled rearwardly and upwardly, for the purposes set forth.

3. The combination with a conveyer-chain link of laterally-extending wings carried by 110

said link, said laterally-extending wings having their front faces inclined rearwardly and upwardly; together with a socket having its front face beveled rearwardly and upwardly and projecting above the side members of the link, for the purposes set forth.

4. In combination with a conveyer-chain link; a pair of laterally-extending wings formed integral with said link, said wings having their front faces beveled rearwardly and upwardly and extending obliquely to the line of travel of the chain.

5. The combination in a conveyer, with a suitable link, of wings projecting laterally from each side thereof, the outer free ends of the wings located in advance of their opposite ends attached to said link, the front faces of the wings being inclined rearwardly.

6. A conveyer comprising links, wings projecting laterally from the links, said wings being inclined relative to the links to direct the material to be conveyed toward the links, and brace-rods located back of the wings and extending between the links and the wings, the outer ends of the braces being secured to

the wings near the outer free ends of the latter.

7. A conveyer comprising a plurality of skeleton links, the links each formed with a socket at their rear ends to receive the front end of the next succeeding link, the front face of each socket being faced to form a scoop, wings carried by the opposite sides of each link, the inner ends of the wings being spaced apart by the width of the link, the scoop-face lying between the sides of the link.

8. A conveyer comprising links socketed at one end, separate wings projecting laterally from opposite sides of each link, the forward end of each socket being faced to form a scoop whose lower edge is approximately on a plane with the lower edges of the wings to coöperate therewith.

In testimony whereof I affix my signature in presence of two witnesses.

MICHAEL GARLAND.
